UNITED STATES PATENT OFFICE.

WILLIAM ALEXANDER MORRIS, OF EL RENO, OKLAHOMA.

HEEL PLATE.

Application filed September 22, 1922. Serial No. 589,829.

To all whom it may concern:

Be it known that I, WILLIAM A. MORRIS, a citizen of the United States, and a resident of El Reno, in the county of Canadian 5 and State of Oklahoma, have invented certain new and useful Improvements in Heel Plates, of which the following is a specification.

This invention relates to heel plates especially adapted for use with elastic heels such as rubber heels or the like, and the object of the invention is to provide a heel plate of this character which may be conveniently and readily, though firmly and 15 securely, organized with a rubber heel and in such manner as not to impair the elastic properties and action of the rubber heel and yet at the same time endow the heel with the desired antislipping and wearing qualities. 20

Another object is to provide a heel plate of this character which may be conveniently produced from a single piece of metal by manufacturing facilities readily available 25 and which is consequently economical and comparatively inexpensive to manufacture, the heel plate being also of such simple construction as to be readily applied to the heel.

Other objects and advantages of the invention reside in certain novel features of the construction, combination and arrangement of parts which will be hereinafter more fully described and particularly pointed 30 out in the appended claims, reference being had to the accompanying drawings forming part of this specification, and in which:

Figure 1 is a fragmentary view, in bottom plan, showing a shoe having a rubber heel equipped with a heel plate embodying the present invention;

Figure 2 is a view in section on line 2—2 of Figure 1;

Figure 3 is a similar view on line 3—3 of Figure 1; and

Figure 4 is a detail perspective view, showing the heel plate.

Referring to the drawings wherein for the sake of illustration is shown the preferred embodiment of the invention, the numeral 10 designates an elastic heel such as a rubber heel or the like which is associated with the shoe in the usual manner.

The heel plate which constitutes the present invention is designated generally at 17

and as shown in the drawings it may be constructed of a single piece of resilient sheet metal formed to provide a body portion 12 of general sector shape, the outer or tread surface of the body portion being serrated or roughened, as at 13, in order that the heel plate may be anti-slipping when in use. Also, as clearly shown in Figure 3 of the drawings the body portion 12 is transversely curved for a purpose which will hereinafter be more fully described. The small end of the body portion 12 merges into a prong 14 which is integral with the body portion and which, though offset slightly from the plane of the body portion, extends longitudinally therefrom and in approximate parallelism therewith. The prong 14 is not, however, exactly parallel with the body portion but inclines slightly 75 from the plane of the body portion in order that the prong may be offset from the body portion and in order that it may become properly embedded in the heel as will be presently described. Preferably, however, 80 the arrangement of the prong with respect to the body portion is such that the longitudinal center line of the body portion when extended also constitutes the longitudinal center line of the prong. As shown in the drawings the prong also tapers from toward its point. A pointed lug 15 is provided and this lug is preferably formed by pressing a portion of the body portion 11 inwardly so as to form the lug integral with 85 the body portion. Also this lug 14 is located at about the center of the body portion and extends substantially at right angles to the plane of the body portion. The free end of the lug is sharpened whereby the lug may be readily associated with 90 the heel.

In applying the heel plate to a heel, the prong 14 is inserted into the material of the heel and the lug 15 is also driven into the body of the heel, as shown in Figure 2. This causes the side edges of the transversely curved body portion 12 to become embedded in the material of the heel. A nail or other fastening device 16 is then 105 driven into the rubber of the heel and through an aperture provided therefor in the lug 15. It is to be noted that the heel plate is curved at the juncture of the prong and body portion, and this together with 110 the manner in which the side edges of the body portion are embedded in the material

of the heel due to the transverse curvature of the body portion relieves the assembly of any sharp edges or shoulders thereby precluding any possibility of the heel plate 5 catching or striking projections or other objects liable to engage shoulders or sharp edges. At the same time the heel plate presents a serrated or roughened surface adapted to prevent slipping and also gives 10 the heel the desired strength and wearing qualities. Referring especially to Figure 2 of the drawings it will be seen that while the heel plate is firmly and securely fastened to the heel it nevertheless in nowise interferes with the elastic or cushioning action of 15 the heel since none of its elements engage the leather making up the shoe or otherwise effect or impair the cushioning properties of the material which comprises the heel.

20 I claim:

25 1. A heel plate for use with elastic heels and comprising a transversely curved body portion adapted to be fitted to the heel in such manner that the side edges of the body portion are embedded in the material of the heel, a prong extending longitudinally from one end of the body portion and inclined slightly with respect to the plane of the body portion, the prong being adapted 30 to be inserted into the body of the heel and

being adapted to lie at a slight distance above the tread surface of the heel, the juncture between the prong and the body portion being curved, a lug integrally formed with the body portion and adapted to be driven into the heel, said lug being apertured, and a fastening device adapted to be driven through the material of the heel and through the aperture of said lug. 35

2. A heel plate for use with elastic heels and comprising a transversely curved body portion having its tread surface curved, a prong extending longitudinally from one end of the body portion and slightly inclined with respect thereto and adapted to be embedded in the material of the heel, and a lug extending centrally of the body portion and formed integral therewith and adapted to be driven into the body of the heel, in combination with a driven fastening device cooperable with said lug. 40

3. A heel plate having a body portion, a lug integral with the body portion intermediate its ends and extending substantially at right angles thereto, said lug being arranged to be driven into the body of a heel, said lug being apertured in such manner as to be adapted to receive a fastening device engageable with a heel. 45 50 55

WILLIAM ALEXANDER MORRIS.
